UNITED STATES PATENT OFFICE

103,560

DESIGN FOR A SLIPPER OR SIMILAR ARTICLE

Jack Barnett, Brooklyn, N. Y.

Application December 18, 1936, Serial No. 66,625

Term of patent 3½ years

To all whom it may concern:

Be it known that I, Jack Barnett, a citizen of Union of Soviet Socialist Republics, residing at Brooklyn, in the county of Kings, State of New York, have invented a new, original, and ornamental Design for a Slipper or Similar Article, of which the following is a specification, reference being had to the accompanying drawing, forming part thereof.

The characteristic features of the design reside in the contour of the upper edge of the vamp wherein said edge towards the inner portion of the slipper, is substantially higher and more

sharply curved than the edge towards the outer portion of the slipper, and in the depressed curve at the back of the counter of the slipper.

Fig. 1 is a perspective view of a slipper showing the new design and as viewed from the front thereof.

Fig. 2 is a perspective view as viewed from the rear.

I claim:

The ornamental design for a slipper or similar article substantially as shown and described.

JACK BARNETT.
